UNITED STATES PATENT OFFICE.

JOHN W. RICE, OF SPRINGFIELD, MASSACHUSETTS.

IMPROVEMENT IN RAILROAD-CAR BRAKES.

Specification forming part of Letters Patent No. 22,455, dated December 28, 1858.

To all whom it may concern:

Be it known that I, JOHN W. RICE, of Springfield, in the county of Hampden, in the State of Massachusetts, have invented certain new and useful Improvements in Car-Brakes for Railroad-Cars; and I do hereby declare that the following is a full, clear, and exact description thereof, reference being had to the accompanying drawing, and letters of reference marked thereon, making part of this specification.

The nature of my invention consists in a new combination and mechanical arrangement of parts, which makes a more simple and effectual arrangement than my former patent bearing date August 3, 1858, and hence an improvement over that.

The improvement consists, first, in dispensing with a bar or rod extending from one brake-beam to the other, which served for one purpose to support or hold the double-fulcrum lever L in its proper place. By this arrangement I suspend the double-fulcrum lever L and brake-rods M M, holding them in their proper position by means of the suspension-bar H and crotch-bolt I, attached to the center truck-beam E. The suspension-bar should be made of spring metal, so as to accommodate the action or tension of the brakes when applied to the wheels, so that the whole of the brakes shall operate simultaneously on all of the wheels together by applying the brakes at either or both ends of the car at the same time, and the double-fulcrum lever L can be set at any angle and held in its proper position by means of the crotch-bolt I and nut J. The tension of the brake-rods M can be regulated by means of the nuts N on the outer end resting against the outside of the brake-beams; or, second, by making what may be called a "continuous brake or connection rod" playing round the loose pulley K, and can be regulated by means of the swivels O O. It will readily be perceived by this arrangement that it is immaterial at which end of the car the brakes are applied, as it is constantly pulling one and the same way; or, by applying the power at either end separately it will relieve the screw at the opposite end; or should either end get out of repair I still have the double-action brake with all its symmetry and simplicity, as either end operates independ-

ently of the opposite end, which result could not be so readily effected were it not for the arrangement of the horizontal pulley K, and should two parties be operating the brakes at the same time at opposite ends of the car, to prevent applying the brakes too powerfully, which would slide the wheels, which is a common evil, as it in a great measure destroys the friction, and also destroys the wheels in an incredibly short time, which frequently seriously affects the finances of many railroad companies, I have obviated the evil and can regulate the power applied and take up slack chain, &c., by means of collars P P on the standard q, that guides the nut R to the screw S, being the only effectual means in use to accomplish the much-desired object of regulating the friction applied to the wheels. With my invention it can be easily accomplished.

To enable others skilled in the art to make and use and apply my invention to railroad-cars, I will proceed to describe its application and operation, to render it plain and distinct. As it will be seen by the drawing, I have a skeleton platform, so that it shows the whole arrangement of parts of the brakes and how they are applied, &c.

A A represent the skeleton platform; B B, bearings between the platform or body of the car and the trucks; C C, side pieces to the trucks; F F, end pieces; E E, the center truck-beam; D D, pedestals; G G, brake-beams; H H, the suspension-bars attached to the center truck-beams E E; I I, the crotch-bolt, and J J the nuts that regulate the angle to the double-fulcrum lever L and holds it up; K, the loose pulley, around which the continuous connection-rod V plays; L L, the double-fulcrum levers; M M, the brake-rods that connect the double-fulcrum lever to the brake-beams M M, and N N the nuts that regulate and confine them to the brake-beams; O O, swivels to regulate the length of the continuous connection-rod V; P P, collars on the standard q to regulate the amount of power applied to the brakes R R, and S S the nut and screw that operate the brakes when the power is applied to the same; T T, the balance-wheels where the power is applied to the screw; V V, the continuous connection-rod, a part of which is made of chain, so as to readily play round the loose pulley K and operate

freely round the pulleys at the ends of the car near where the chain is attached to the nuts R. R.

Having thus fully described the nature and the manner of applying my invention to rail-road-cars, I only claim my improvements and do hereby disclaim the other parts, some of which are already secured to me by Letters Patent by the United States Patent Office, which patent bears date August 3d, 1858.

What I claim as new, and desire to secure by Letters Patent, is—

1. The suspension-bar H and crotch-bolt I and nut J when arranged and operating in the manner and for the purposes substantially as described.

2. The continuous rod V and loose pulley K in combination with the suspension-bar H and crotch-bolt I and nut J when arranged and operating substantially as and for the purposes set forth.

3. The loose collars P P, on the standard q when applied in the manner and for the purposes substantially as set forth.

In testimony whereof I hereunto set my hand this 15th day of November, A. D. 1858.

JOHN W. RICE.
